UNITED STATES PATENT OFFICE.

EDMOND W. T. RICHMOND, OF ROMFORD, ENGLAND.

DESIGN FOR A GAS-STOVE.

SPECIFICATION forming part of Design No. 33,886, dated January 8, 1901.

Application filed December 14, 1900. Serial No. 39,928. Term of patent 7 years.

To all whom it may concern:

Be it known that I, EDMOND WALTER TYRRELL RICHMOND, a subject of the Queen of Great Britain, residing in Summercourt, Romford, in the county of Essex, England, have invented and produced a new and original Design for Gas-Stoves, of which the following is a specification.

The accompanying drawing shows a perspective view of a gas-stove embodying my design.

The leading features of my design are the base portion A, having the front molding *a* and top molding *a'* and the panels B, the body portion C, having the vertical panels *c*, bounded by molding *c'*, and the top or cap

portion D, having the horizontal molding *d* along its lower edge. The molding for the panel, as shown, stands out in relief. The panels in the base portion have vertical slots or openings between them; and between the panels of the body portion there are ornamental handles vertically arranged.

I claim—

The design for a gas-stove, substantially as herein shown and described.

In testimony whereof I have hereunto subscribed my name.

EDMOND W. T. RICHMOND.

Witnesses:

KATHARINE MACMAHON,
EDWARD C. DAVIDSON.
